UNITED STATES PATENT OFFICE.

FRANK M. DAVIS, OF MILWAUKEE, WISCONSIN.

LUBRICATING SYSTEM FOR ENGINES.

1,113,204.

Specification of Letters Patent.

Patented Oct. 13, 1914.

Application filed July 17, 1913. Serial No. 779,444.

To all whom it may concern:

Be it known that I, FRANK M. DAVIS, a citizen of the United States, and resident of Milwaukee, in the county of Milwaukee and State of Wisconsin, have invented new and useful Improvements in Lubricating Systems for Engines, of which the following is a description, reference being had to the accompanying drawings, which are a part of this specification.

This invention relates to improvements in lubricating systems for engines and more particularly to engines of the internal combustion type.

15 It is one of the objects of the present invention to provide a lubricating system which is adapted to oil the cranked shaft of the engine continuously while the engine is in operation.

20 A further object of the invention is to provide a lubricating system in which the same oil may be used over and over again.

A further object of the invention is to provide a lubricating system in which the 5 oil flowing from the bearing is screened and cleaned from foreign matter before it is again fed to the bearings.

A further object of the invention is to 30 provide a lubricating system of simple construction which is strong and durable and is well adapted for the purpose described.

With the above and other objects in view, the invention consists of the improved lubricating system and its parts and combinations as set forth in the claims, and all 35 equivalents thereof.

In the accompanying drawings in which the same reference characters indicate the same parts in all of the views: Figure 1 is a 40 vertical sectional fragmentary view of an opposed horizontal internal combustion engine provided with the improved lubricating system; Fig. 2 is a similar view in horizontal section; and Fig. 3 is a detail view of 45 the lower portion of the crank case and the oil pump.

Referring to the drawings the numeral 8 indicates the opposed cylinders, 9 the crank case, 10 the cranked shaft, 11 the cam shaft, 50 12 the pistons and 13 the connecting rods between the pistons and the cranked shaft. The connecting rods are of tubular form and their bores 14 (only one being shown) extend to points adjacent to the piston pins 15 and the cranked shaft and are in communication therewith by oil holes 16. Elongated 55 inlet charging openings 17 for the connect-

ing rods are provided in the upper portions of said rods which extend along a considerable distance.

The cam shaft 11 has a geared connection 60 18 with the cranked shaft and the gear of the cam shaft is in mesh with a pinion 19 mounted on a worm shaft 20 journaled in the upper portion of the crank case 9. The 65 worm 21 of the worm shaft is in mesh with a worm pinion 22 which is mounted on a vertically extending pump shaft 23 and the said pump shaft extends out of the crank case and downwardly to a point adjacent to 70 the lower part of the crank case and is connected to a gear pump 24.

The casing 25 of the gear pump extends 75 to and is bolted to the lower portion of the crank case and is provided with inlet and outlet passageways 26 and 27 respectively which are in communication with the crank case chamber 29 and with opposite sides of the pump.

The inlet passageway 26 is in communication with the bottom portion of the crank chamber and is adapted to receive the surplus oil which flows from the bearings and is screened through the screen 30 which covers the bottom portion of the crank chamber 85 above said inlet opening and is spaced therefrom a short distance to provide an oil supply chamber 31.

Discharge pipes 32 and 33 positioned 90 within the crank chamber and connected to the passageway 27 extend upwardly to positions so that their spouted ends 34 will direct the oil into the tubular connecting rods and on the other bearings of the crank shaft.

The inlet passageway 26 is provided with 95 a valve 35 for regulating the flow of oil to the pump and the feed to the bearings.

In use the rotation of the gear pump will draw up the oil from the crank case and force it on the bearings and into the tubular 100 connecting rods and as the connecting rods are oscillated up and down the oil within the said rods will alternately flow to the opposite ends of the rods and lubricate the bearings thereof through the oil holes of the rods. 105

The surplus oil flowing from or discharged from the bearings will drop to the bottom portion of the crank case and pass through the screen and the screened oil will again be drawn into the pump and take the 110 same course as before described while the engine is in operation.

From the foregoing description it will be seen that the lubricating system is of very

simple construction and is well adapted for the purpose described.

What I claim as my invention is:

1. A lubricating system, comprising an engine, having a cylinder and a crank case, a substantially horizontal hollow connecting rod forming part of the engine and having an inlet opening in its upper portion, a pipe within the crank case extending from a point at the bottom portion thereof to a position to spray a stream of oil into the connecting rod through said opening, and a pump for forcing oil through said pipe from the bottom portion of the crank case.
  - 15 2. A lubricating system, comprising an engine having a cylinder and a crank case, a substantially horizontal tubular connecting rod forming part of the engine and having an inlet opening in its upper portion, a pipe within the crank case and extending from a point near the bottom portion of the crank case to a position to spray a stream of oil into the connecting rod opening and to the engine bearings, and a pump for circulating the oil from the bottom portion of the crank case upwardly through the pipe.
  - 20 3. A lubricating system, comprising an engine having a cylinder and a crank case, a substantially horizontal tubular connecting rod forming part of the engine and having an inlet opening in its upper portion, a pump positioned adjacent to the crank case and having an inlet and an outlet passageway, the inlet passageway being in communication with the bottom portion of the crank chamber, a pipe connected to the outlet passageway and extending to a position to spray a stream of oil into the bore of the connecting rod and to the engine bearings, a
  - 25 40 cam shaft within the crank case and driven by the cranked shaft, a pump shaft extending from the pump into the crank case, and a driving connection between the cam shaft and the pump shaft.
  - 45 5. A lubricating system, comprising an engine having a cylinder and a crank case, a substantially horizontal tubular connecting rod forming part of the engine and having an inlet opening in its upper portion, a pump positioned adjacent to the crank case and having an inlet and an outlet passageway, the inlet passageway being in communication with the bottom portion of the crank chamber, a pipe connected to the outlet passageway and extending to a position to spray a stream of oil into the bore of the connecting rod and to the bearings of the engine, a cam shaft within the crank case and driven by the cranked shaft, a pump shaft extending from the pump into the crank case, and a worm and gear connection between the cam shaft and the pump shaft.
  - 55 60 6. A lubricating system, comprising an

In testimony whereof, I affix my signature, in presence of two witnesses.

FRANK M. DAVIS.
